(Cl. D9—2)

Figure 1 is a perspective view of the liquid chemical applicator for toilet bowls and the like, showing my new design;

Figure 2 is a side elevation of the applicator;

Figure 3 is a bottom plan view of the applicator; and

Figure 4 is an enlarged end elevation of the applicator handle member.

The characteristic feature of my design for the applicator disclosed resides in the handle member.

I claim:

The ornamental design for a liquid chemical applicator for toilet bowls and the like, as shown and described.
